UNITED STATES PATENT OFFICE.

PERCY J. WILLIAMS, OF SAN FRANCISCO, CALIFORNIA, ASSIGNOR TO WILLIAMS BROS.
AIRCRAFT CORPORATION, A CORPORATION OF CALIFORNIA.

ACCELERATOR.

Application filed September 25, 1922. Serial No. 590,233.

The present invention relates to improvements in internal combustion engine accelerators of the type which cooperates with hand operated mechanism for operating the 5 throttle valve of the carburetor and is constructed and arranged to permit of independent operation of the foot and hand controlled operating means whereby the operation of the foot mechanism will not effect 10 the hand operated means and vice versa.

One of the objects of the invention is to provide a simply constructed and highly efficient accelerator mechanism which may be readily and easily incorporated with standard 15 throttle controlling mechanism and certain makes of motor cars without necessitating materially the changing of the construction and arrangement of the standard mechanism or requiring the employment of 20 skilled labor.

Another object of the invention is to provide an accelerator which consists of a minimum number of compactly arranged parts which operate in a reliable manner to 25 provide for an effective control of the carburetor throttle valve.

The invention further resides in the particular combination, inter-relation and relative arrangement of specially arranged and 30 novelly constructed elements of the mechanism, which arrangement of elements provides for a general improvement in accelerators by way of insuring smoothness and 35 ease of operation thereof, compactness, simplicity, and decreased cost of production.

The invention possesses other advantages and features some of which, with the foregoing will be set forth at length in the following description where I shall outline in 40 full that form of the invention which I have selected for illustration in the drawings accompanying and forming a part of the present specification. In said drawings I have shown one form of the construction of my 45 invention, but it is to be understood that I do not limit myself to such form since the invention as expressed in the claims may be embodied in a plurality of forms.

50 Referring to the drawings:—

Fig. 1 represents a perspective view of the device of my invention showing it as it would appear when in use and as attached to the hand control means and carburetor.

55 Fig. 2 represents a fragmentary top plan view of the device of my invention.

Fig. 3 represents a side elevation of the pedal shown partly in section and as connected with the flexible operating means.

Fig. 4 is a perspective view of a modified form of the invention showing the hand operated mechanism and carburetor as associated therewith.

Fig. 5 is a top plan view of a part of the mechanism.

Fig. 6 is a fragmentary perspective view 65 of a modified form of the invention.

In the drawings wherein there is illustrated in detail one embodiment of the invention, the numeral 1 designates a foot-board of an automobile, 2 the steering mechanism and 3 the standard hand operated mechanism, the latter including a crank arm 4 which is adapted for connection with the crank arm 5 of the carburetor 6 through the accelerator 70 of my invention, as will be later more fully 75 described.

The accelerator of my invention comprises essentially a rod 7, one end of which is pivoted as at 8 to the carburetor crank arm 5, the other end of which is connected with 80 the crank arm 4 through the instrumentality of specially constructed means 9 forming a part of the invention. The means 9 and arms 7 comprise a resilient or longitudinally 85 extensible connection between the two crank arms. The means 9 includes an angular bracket consisting of a top plate 9', depending end flanges 10 and 11 and a lateral extension 12 carried by the top plate 9'. The top plate 9' is provided adjacent one end 90 with upstanding ears 13 to which the crank arm 4 is pivoted. The rod 7 slidably extends through openings in the end pieces 10 and 11 and is normally held in its extended position with reference to the means 95 8, by an expansion spring 15 surrounding said rod and engaging at its ends, a rod carried stop member 16 and the inner side of the end piece 10.

The accelerator includes a pedal 17 pivot- 100 ed as at 18 on a base or mounting 19 which in turn is secured in any suitable manner to the floor board 1. Connected with the pedal 17 is a flexible operating element, preferably a wire, 20, which element is slidable in a flexible cable or tube 21. The tube 21 is seated in a socket 22 on the pedal mounting 19 and it is made fast to the bracket of the member 8 by an angular clamp 23 secured to the flange 11 and top plate 9' by a screw 24. 110

The clamp is provided with a lug 25 adapted to extend through an opening 26 in the top of the plate so as to be securely held in place. The wire element 20 extends beyond the tube or cable 21 and at its free end is fastened as at 27 to one end of a bell crank 28. The bell crank is pivoted intermediate of its ends as at 29 to the extension 12 and at its other end is connected with an enlarged portion 30 on the rod 7, through the instrumentality of a pin and slot joint 31. By having the ends of the cable 21 held stationary in the socket 22 and clamp 23, when the pedal 17 is depressed, the wire 20 is pulled and rocks the bell crank 29, causing the rod 7 to be moved so as to open the throttle valve of the carburetor. This action is against the action of the spring 15 and independent of the bracket whereby the bracket and hand operated means 3 will not be effected upon such movement of said rod 7. It will thus be seen that the foot operated means of the accelerator is actuated without causing any interference with or movement of the hand operated means 3. By causing the wire 20 to pull directly on the bell crank 28 when the pedal is depressed, and due to the arrangement of the bracket and bell crank, an easy and smooth movement of the rod 7 will be effected with a minimum amount of exertion expended to depress the pedal. Upon release of the pedal, the spring 15 will be operated to quickly return the parts to normal position and close the throttle valve.

35 When the hand operated means is actuated, the crank arm 4 in being turned causes the bracket 9 and rod 7 to be moved bodily thereby operating the throttle valve crank arm. Since the wire 20 and cable or tube 21 are flexible, this bodily movement of the mechanism will not effect operation of the pedal. By this arrangement it will be seen that either the hand or foot operated means may be operated without one affecting the other. By this arrangement including the bracket, bell crank and connections of both with the rod 7 and flexible elements operating the bell crank, a great deal of friction is eliminated in the operation of the mechanism and the accelerator is thereby prevented from sticking and otherwise proving uncertain in operation. The entire device is simple, small, compact and may be readily and easily attached to various makes of automobiles.

In the modified form of the invention illustrated in Figs. 4 and 5, 33 designates a foot board of an automobile, 34 the steering mechanism, 35 the throttle valve crank arm, 60 38 the hand operated crank arm and 39 an auxiliary crank arm loosely mounted on a rod 40 forming a part of the mechanism 35.

The resilient or longitudinally extensible connection between the crank arms 39 and 65 37 comprise an angular bracket 41 including

a longitudinal body plate 42, an angular lateral projection 43 at one end thereof and a similar projection 44 at the opposite end. The body plate 42 is pivotally connected as at 45 with the crank arm 38 and similarly 70 connected as at 46 with the crank arm 39, said pivot points being spaced apart and located at points between the ends of the body plate.

A slide member 47 is movable longitudinally in a slot 48 formed in the body plate 42 and has connected therewith one end of a rod 49, the other end of which rod is pivotally connected as at 50 with the crank arm 37 on the carburetor. The slide member is 80 provided with an angular extension 51 disposed on the side of the plate 42 opposite that on which the rod 49 is disposed and to this angular projection 51 one end of a retractile spring 52 is connected. The other end of the spring is secured in any suitable manner to the projection 44 at the forward end of the body plate, and said spring thereby serves to normally hold said rod extended and the throttle valve closed. 90

As a means for operating the rod 49 without causing movement of the plate or bracket 41 and the hand operated mechanism 35, I employ the same means as provided in the previously described embodiment of the invention, which means includes a pedal mounting 53 on the floor board, a pedal 54 thereon, a flexible cable 55 and a flexible, preferably wire, element 56, slidably mounted within the cable. The wire 56 is connected with the pedal and the adjacent end of the cable 55 is stationarily connected with the pedal mounting 53. The other end of the cable is rigidly secured in a sleeve or socket member 57 forming a 100 part of the slide member 47 and the other end of the flexible element is extended beyond the member 57 and secured by suitable clamping means 58 to the angular projection 43 on the bracket 41. 110

When the pedal is depressed, a force is transmitted through the flexible wire element such as will cause the flexible cable 55 to be moved longitudinally relative to the wire element whereby the slide member attached to said cable will be moved in the slot 48 in the direction of the angular projection 43. This will cause the arm 49 to be moved correspondingly and the throttle valve to be opened. This action takes place without causing movement of the bracket 41 and hand operated mechanism 35. The spring 52 serves to return the parts to normal position upon release of pressure upon the pedal. 115

When the hand operated mechanism crank arm 38 is turned, the bracket 41, slide 47 and rod 49 are moved bodily as one and cause the throttle valve crank arm 120 to be operated so as to open the throttle 130

valve. Due to the flexible connections between the bracket and the pedal, this action will not cause the pedal to be actuated. When the bracket 41 is moved bodily the auxiliary crank arm 39 turns freely on the rod 40 and causes the bracket to be moved in a straight line instead of arcuately, thereby lessening friction, making the operation of the apparatus simple and reliable and avoiding sticking or jamming of the moving parts. The construction of this form of the invention is compact, simple and such that it may be readily and easily attached to a motor vehicle and operated in an easy and reliable manner to control the throttle valve either through the hand or foot operated means without causing the action of one to interfere with the other.

As shown in Fig. 6 of the drawings, the modified form of the accelerator comprises a member 59 in the form of a lever, which is pivoted at one end as at 60 to the hand operated crank arm 61, and at its other end is pivotally connected as at 62 with one end of a movable member 63, the latter in the form of a lever. A spring 64 is mounted on the pivot 62 and engages with stop members 65 in such manner as to tend to force the members 59 and 63 apart. The other end of the member 63 is pivoted as at 66 to an intermediate portion of a rod 67, the portion 68 of which is adapted for connection with the throttle valve crank arm, not shown. The rod 67 is slidably mounted on a guide member 69 carried on the first named member or lever 59.

A flexible wire element 70 of the same arrangement as employed in the other form of the invention, and connected with foot operated mechanism, not shown, operates within a flexible cable 71, likewise connected with the foot operated mechanism. One end of the cable 71 is fixed to a member 72 carried on the movable member 63, which member 72 may be pivotally mounted as shown. The wire 70 extends beyond the member 72 and is stationarily held in a fastening element 73 on said member 59, the member 73 being preferably pivoted, as shown. As regards to the action of the flexible elements 71 and 70, the same operation takes place as in the form of the invention shown in Figs. 4 and 5. When the pedal, not shown, is depressed, the wire 70 is acted upon in such manner that the cable 71 slides relative to the wire and moves the member 63 on its pivot 62 without moving the lever or member 59. This causes the rod 67 to be moved and the throttle valve, not shown, to be operated. When the hand operated crank arm 61 is operated, the members 59 and 63, also the rod 67 are moved bodily and thereby pro-

vide for controlling the carburetor without operating the foot operated mechanism. The entire arrangement as to the members 59, 63 and 67, comprises a longitudinal extensible or resilient connection between the hand operated and throttle valve crank arms.

I claim:

1. In combination with the throttle valve crank arm and the hand operated crank arm of the throttle valve controlling mechanism of an internal combustion engine, a member pivoted to the hand operated crank arm, another member having connection with the throttle valve crank arm, a movable member on the first named member to which the second named member is connected, a pedal, a flexible element secured at one end to the pedal and at its other end to the first named member and a flexible cable through which said flexible member is movable, which cable is fastened to said movable member and stationarily held at a point adjacent to said pedal and a spring tending to hold said second named member extended.

2. In combination with the throttle valve crank arm and the hand operated crank arm of the throttle valve controlling mechanism of an internal combustion engine, a member pivoted to the hand operated crank arm, another member having connection with the throttle valve crank arm, a movable member on the first named member to which the second named member is connected, a pedal, a flexible element secured at one end to the pedal and at its other end to the first named member and a flexible cable through which said flexible member is movable, which cable is fastened to said movable element and stationarily held at a point adjacent to said pedal, a spring tending to hold said second named member extended, a stationary member and a link connection between said stationary member and the first named member.

3. The combination with the throttle valve crank arm and the hand operated crank arm of the throttle valve controlling mechanism of an automobile, of a member pivoted to the hand operated crank arm, another member pivoted to the throttle valve crank arm, a movable member on the first named member to which the second named member is connected, a pedal, a flexible element secured at one end of the pedal, a flexible cable through which the flexible element is movable, said cable and flexible element being, one of them connected with the first named member, and the other of them connected with the movable member and a spring tending to hold the second named member extended.

PERCY J. WILLIAMS.
